UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR CARPET.

SPECIFICATION forming part of Design No. 11,666, dated March 2, 1880.

Application filed January 17, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

At the center of the design is the representation of a group of calla-lilies, A, rising from water, in which are water-lilies B. Surrounding the lily effects are tropical floral designs and foliage C D E E, and above these is a bouquet, F. G G are sections of Japanese work, 15 on which are representations of storks H H. I represents another section of Japanese work. The remaining portions of the design are composed of moss-work J, with berries and floral designs K L.

20 I claim—

1. The design for a carpet, comprising the group of calla-lilies, as shown.

2. The design for a carpet, comprising the groups of calla and water lilies, as shown.

3. The design for a carpet, comprising the 25 groups of calla and water lilies surrounded by floral designs, as shown.

4. The design for a carpet, comprising the sections of Japanese work with storks thereon, as set forth.

5. The design for carpets, consisting of the 30 floral designs A B C D E F K L, Japanese work G I, and moss-work J, as set forth.

In testimony whereof I have signed my name to this specification, in the presence of 35 two subscribing witnesses, this 15th day of January, 1880.

THOMAS J. STEARNS.
